UNITED STATES PATENT OFFICE.

BENEDYKT A. KASZINSKI, OF FAIRFIELD, CONNECTICUT.

ARTICLE OF FURNITURE.

1,405,420.

Specification of Letters Patent. Patented Feb. 7, 1922.

Application filed October 20, 1921. Serial No. 509,028.

To all whom it may concern:

Be it known that I, BENEDYKT A. KASZINSKI, a citizen of Poland, residing at Fairfield, in the county of Fairfield and State 5 of Connecticut, have invented certain new and useful Improvements in Articles of Furniture, of which the following is a specification.

This invention relates to certain new and 10 useful improvements in articles of furniture and has particular reference to the provision of an improved form of couch.

The primary object of the invention is to 15 provide a couch of cushion construction and provided with a spring opened sliding drawer releasable upon depression of one 20 of the springs of the couch cover, means being provided to normally prevent release of the drawer upon depression of said spring but being removable for allowing release of the drawer so that the drawer may be 25 opened only by an authorized person.

Another object of the invention is to provide a couch with a slidable spring opened 30 drawer and latching means for holding the drawer closed, the couch being provided with a pivoted leg for releasing said latching means.

With the above general objects in view, 35 the invention consists in the novel form, combination and arrangement of parts hereinafter more fully described in connection with the accompanying drawings and in which like characters of reference indicate corresponding parts throughout the several views.

In the drawings,

Figure 1 is a top plan view of a couch 40 constructed in accordance with the present invention, the cover of the couch being partly broken away to reveal the mechanism located interiorly of the couch.

Figure 2 is a view partly in vertical longitudinal section and partly in side elevation 45 of the device shown in Figure 1.

Figure 3 is a vertical transverse sectional view taken upon line III—III of Figure 2 showing the bar for preventing release of the drawer latch in its normal operative 50 position.

Figure 4 is a view similar to Figure 3 with

said bar removed or inoperatively disposed and the catch depressed to released position,

Figure 5 is a vertical transverse sectional view taken upon line V—V of Figure 2, the pivoted leg being shown in catch releasing 55 position by dotted lines, and

Figure 6 is a fragmentary longitudinal sectional view taken substantially upon line VI—VI of Figure 1 but with the drawer 60 open.

Referring more in detail to the several views, the couch illustrated consists of a pair of side members preferably constructed of wood and denoted by the numeral 5, said members 5 being rigidly connected in spaced parallel relation in any suitable manner as by means of a bottom 6, the open top of the frame construction thus presented being closed by a covering 7 of a suitable fabric 65 or leather in the usual way, suitable vertical helical springs 8 of the compression type being disposed between the covering 7 and the bottom 6 for providing a yielding surface upon which a person may recline with 70 comfort. The side members 7 are extended upwardly as at 9 in the usual manner to provide the head of the couch and the bottom 6 is supported at the required elevation 75 above the floor by means of legs 10 at the foot of the couch and legs 11 at the head of the same.

The foot end of the frame is provided with an opening through which a drawer 12 of the sliding type may be projected, said 80 drawer being slidably disposed upon the bottom 6 and being limited in outward movement by means of a pin 13 projecting upwardly from the bottom 6 and engaging a longitudinal groove 14 in the bottom of the 85 drawer 12. A pair of uprights 15 are fastened to the bottom 6 inwardly of the drawer 12 and one end of a helical compression spring 16 is fastened to each upright 15 and to the back wall of the drawer 12 so as to normally 90 project the drawer to open position as illustrated in Figure 6, the springs 16 being compressed when the drawer is closed as shown 95 in Figures 1 and 2.

One of the springs 8 which support the covering 7 and which is nearest the foot end of the couch has a horizontal transversely ar-

ranged bar 17 fastened thereto near its upper end so that said bar 17 projects inwardly as shown in Figure 3, the bar 17 having an upwardly projecting pin 18 upon its inner 5 free end arranged to engage in an opening provided as at 19 through the inner end of an angular keeper 20 whose vertical flange is rigidly fastened to the back or rear wall of the drawer 12. The arrangement is such 10 that when the spring which carries the bar 12 is in its normal expanded condition and the drawer 17 is closed, the pin 18 engages the keeper 20 and holds the drawer closed although the pin 18 may be readily disengaged from the keeper 20 upon depression of this particular spring 8 by applying pressure to the upper end of the latter as shown 15 in Figure 4 thereby permitting the drawer 12 to be immediately automatically opened 20 by the springs 16. It is desirable to prevent disengagement from the pin 18 from the keeper 20 by an unauthorized person or accidentally should a person lying upon the couch depress the spring 8 which carries 25 the bar 17 and for this purpose, a transverse strip 21 is disposed above the bar 17 and keeper 20 so as to overlie the latter when the drawer 12 is closed and so that the strip 21 will yield downwardly for depressing 30 the horizontal flange of the keeper 20 so as to maintain the latter engaged with the pin 18 upon depression of the spring 8. The pin 18 will thus be prevented from being accidentally disengaged from the keeper but the 35 strip 21 is slidably mounted for movement transversely of the couch so as to be withdrawn out of the path of the keeper 20 should opening of the drawer be desired. As shown in Figures 1, 3, and 4, the strip 40 21 may be slidably mounted for limited movement in a transverse direction by means of a pin 22 engaging a longitudinally elongated slot 23 in the strip 21 and rigidly carried by one of the side members 5 having 45 a slot through which the strip 21 extends. The strip 21 may have an enlargement 24 upon one end exposed at all times so that the strip may be readily withdrawn and the other side member 5 may be slotted as shown 50 at 25 in Figure 3 to receive the opposite end of the strip 21 when the latter is operatively disposed above the keeper 20.

As an additional means for safeguarding against opening of the drawer 12 by an unauthorized person, an additional latching means is provided. This additional latching means embodies a relatively long bar 26 having one end fastened to the back of the drawer 12 and slidably mounted for longitudinal movement upon the bottom 6 through guides 27, the bar 26 extending to a point above one of the legs 11 at the head of the couch when the drawer is closed and having an upwardly projecting pin 28 at its 65 end normally engaged behind a lateral pin

29 which is fixed to an upwardly extending arm 30 formed upon the upper end of the adjacent leg 11, said leg 11 being pivoted for transverse swinging movement as at 31 through the bottom 6. A helical tension 70 spring 32 has one end fastened to a side member 5 and extends transversely of the couch where its other end is attached to the upper end of the arm 30 of the leg 11 which is pivoted. The spring 32 thus normally 75 maintains the pivoted leg 11 in vertical position with the pin 28 engaged behind the pin 29 so that the drawer is effectively maintained in a closed position. By simply kicking or otherwise swinging the leg 11 inwardly as indicated by dotted lines in Figure 5, against the action of spring 32, the pin 29 will be disengaged from the pin 28 and the drawer 12 will then be permitted to automatically open under the action of the 80 springs 16.

Assuming that the parts are disposed as shown by full lines in Figures 1, 2, 3, and 5, an authorized person may readily open the drawer by simply withdrawing the strip 90 21 and depressing the spring 8 which carries the bar 17 as shown in Figure 4 thereby disengaging the pin 18 from the keeper 20, and at the same time swinging the pivoted leg 11 inwardly as shown by dotted lines in 95 Figure 5 until the pin 29 is disengaged from the pin 28, at which time the springs 16 automatically open the drawer 12. A reversal of this operation will obviously cause the drawer to be effectively held in closed 100 position. Assuming that an unauthorized person not familiar with the structure desired to open the drawer 12, it is more than likely that he will not recognize the necessity for withdrawing the strip 21 and if this is 105 not done, depression of the spring 8 which carries the bar 17 will simply cause the strip 21 to be flexed downwardly so as to keep the keeper 20 flexed downwardly in engagement with the pin 18 whereby the drawer 110 will be prevented from opening. This will be the case even though the person should discover that the swinging of the pivoted leg 11 effected some release for the drawer. It will thus be seen that I have 115 provided a simple and practical construction of catch having an efficient sliding drawer locking mechanism for the safekeeping of valuables or the like.

What is claimed as new is:

1. In a couch construction, a frame having a flexible covering with internal supporting springs for the covering, a drawer slideable in the frame, means to automatically open said drawer, and means to latch the drawer 125 in closed position against the action of said last named means including a member operable upon depression of one of said springs for releasing the drawer.
2. In a couch construction, a frame having 130

a flexible covering with internal supporting springs for the covering, a drawer slidable in the frame, means to automatically open said drawer, means to latch the drawer in closed position against the action of said last named means including a member operable upon depression of one of said springs for releasing the drawer, and means associated with said spring for preventing release of the latching means upon depression of said spring, the last named means being movable for permitting release of the latching means when desired.

3. A couch comprising spaced parallel side members rigidly connected by a bottom member and having a flexible covering, vertically disposed helical springs arranged between the bottom and the covering and between said side members for yieldingly supporting said covering, a drawer slidably mounted in the foot end of the couch upon said bottom member, springs associated with said drawer for normally yieldingly urging the latter to open position, legs supporting the side members, one of said legs being pivoted, and means for latching the drawer in closed position releasable upon swinging of said pivoted leg.

4. A couch comprising spaced parallel side members rigidly connected by a bottom member and having a flexible covering, vertically disposed helical springs arranged between the bottom and the covering and between said side members for yieldingly supporting said covering, a drawer slidably mounted in the foot end of the couch upon said bottom member, springs associated with said drawer for normally yieldingly urging the latter to open position, legs supporting the side members, one of said legs being pivoted, means for latching the drawer in closed position releasable upon swinging of said pivoted leg, and yieldable means to normally hold the pivoted leg in operative supporting position with the drawer latching means operative.

5. A couch comprising a frame having a covering, depressible springs for supporting said covering, a drawer slidable in the foot end of the couch and having a keeper fixed to the rear wall thereof, one of said springs having a latch pin engageable with the keeper when the drawer is closed and the covering supporting springs are expanded and releasable from the keeper upon depression of said one spring.

6. A couch comprising a frame having a covering, depressible springs for supporting said covering, a drawer slidable in the foot end of the couch and having a keeper fixed to the rear wall thereof, one of said springs having a latch pin engageable with the keeper when the drawer is closed and the covering supporting springs are expanded and releasable from the keeper upon de-

pression of said one spring, and means to automatically open the drawer upon depression of said spring.

7. A couch comprising a frame having a covering, depressible springs for supporting said covering, a drawer slidable in the foot end of the couch and having a keeper fixed to the rear wall thereof, one of said springs having a latch pin engageable with the keeper when the drawer is closed and the covering supporting springs are expanded and releasable from the keeper upon depression of said one spring, means to automatically open the drawer upon depression of said spring, and means operable at will to prevent release of the pin from the keeper upon depression of said spring.

8. A couch comprising a frame having a covering, depressible springs for supporting said covering, a drawer slidable in the foot end of the couch and having a keeper fixed to the rear wall thereof, one of said springs having a latch pin engageable with the keeper when the drawer is closed and the covering supporting springs are expanded and releasable from the keeper upon depression of said one spring, means to automatically open the drawer upon depression of said spring, and means operable at will to prevent release of the pin from the keeper upon depression of said spring, said last named means comprising a resilient strip disposed above the keeper.

9. A couch comprising a frame having a covering, depressible springs for supporting said covering, a drawer slidable in the foot end of the couch and having a keeper fixed to the rear wall thereof, one of said springs having a latch pin engageable with the keeper when the drawer is closed and the covering supporting springs are expanded and releasable from the keeper upon depression of said one spring, means to automatically open the drawer upon depression of said spring, means operable at will to prevent release of the pin from the keeper upon depression of said spring, said last named means comprising a resilient strip disposed above the keeper, and slidably transversely of the couch into and out of position above the keeper.

10. In a couch construction, the combination with a frame having a flexible covering, and supporting springs for said covering, a drawer slidable in the frame beneath said covering, and means for locking the drawer in closed position releasable by depression of one of said springs.

11. In a couch construction, the combination with a frame having a flexible covering, and supporting springs for said covering, a drawer slidable in the frame beneath said covering, means for locking the drawer in closed position releasable by depression of one of said springs, and means operative at

will to prevent release of the drawer upon depression of said spring.

12. In a couch construction, the combination with a frame having a flexible covering, and supporting springs for said covering, a drawer slideable in the frame beneath said covering, means for locking the drawer in closed position releasable by depression of

one of said springs, means operative at will to prevent release of the drawer upon depression of said spring and means to yieldingly normally urge the drawer to open position.

In testimony whereof I affix my signature.

BENEDYKT A. KASZINSKI.
